UNITED STATES PATENT OFFICE.

GOTTLIEB L. E. KLINGBEIL, OF OMAHA, NEBRASKA.

DEVICE FOR FACILITATING THE LUBRICATION OF VEHICLE-SPRINGS.

1,374,583.

Specification of Letters Patent. Patented Apr. 12, 1921.

Application filed October 27, 1920. Serial No. 419,786.

To all whom it may concern:

Be it known that I, GOTTLIEB L. E. KLINGBEIL, a citizen of the United States of America, residing at Omaha, in the county of Douglas and State of Nebraska, have invented certain new and useful Improvements in Devices for Facilitating the Lubrication of Vehicle-Springs, of which the following is a specification.

10 This invention relates to a device for facilitating the lubrication of vehicle springs. It has for its object to provide an improved article of this nature by means of which the leaves of vehicle springs may be quickly 15 separated a sufficient distance to permit of the insertion of a suitable lubricant therebetween.

Further objects and advantages of the invention will be set forth in the detailed 20 description which follows.

In the accompanying drawings:

Figure 1 is a side elevation of the device constituting the subject matter of the present invention;

25 Fig. 2 is a perspective view of the base with the standards broken away;

Fig. 3 is a detailed view illustrating the holding cleats hereinafter described;

30 Fig. 4 is a perspective view of one of the spring engaging teeth and the holder by which it is carried; and

Fig. 5 is a transverse vertical sectional view through the base.

Like numerals designate corresponding 35 parts in all of the figures of the drawings.

Referring to the drawings 5 designates the base of the structure which is preferably rectangular in form and has an open central portion which receives a block 6 that 40 is pivoted for rocking movement about a longitudinal axis. The pivoting means for the block 6 is constituted by studs 7 and 8 which project from the opposite ends of the block 6 and pass through the end portions 45 of the base 5. These studs have nuts 9 and 10 threaded upon them exteriorly of the base. One end of the block 6 is provided with a pair of studs 11 and 12 disposed upon opposite sides of the block, said studs being 50 adapted to enter recesses 13 and 14 formed in the adjacent end wall of the base 5. Thus if the nut 9 be screwed up the block 6 will be drawn bodily toward the adjacent end wall of the base 5 to cause the said studs 55 to engage in the recesses and thus hold the block 6 against rocking movement, while,

upon the other hand, if the nut 10 be screwed up the block 6 will be pulled bodily in the opposite direction and will move the studs out of the recesses and leave the block 6 free 60 to rock about its longitudinal axis, it being understood that when the block has been moved to the desired position as hereinafter described the nut 10 will be tightened sufficiently to bind it in its adjusted position. 65

The block 6 is provided with a cavity 15 in which the lower end portions of standards 16 and 17 are pivoted upon transverse pivots 18 and 19. The pivot 19 is adapted to be received in any of the openings 20 70 formed in the block 6 so that the standard 17 may be bodily adjusted toward and from the standard 16.

An operating handle 21 is pivoted at 22 to the standard 16 and its inner end is 75 pivotally connected at 23 to a link 24. The other end of this link carries a roller 25 operable between the outer edge wall 26 of the standard 17 and a guide 27 carried by said standard. Thus it is manifest that if 80 the handle be moved upwardly to bring the handle and link into substantial alinement with each other, the standards 16 and 17 will be separated while if said handle 21 be swung downwardly said standards will be 85 moved toward each other. This movement of the standards toward each other brings dogs 28 and 29 toward each other. These dogs are mounted for vertical adjustment upon the upper ends of the standards and comprise 90 teeth 30 and 31 adapted to enter between the leaves of vehicle springs, said teeth being of such wedge formation as to spread the leaves apart for the purpose set forth. The teeth 30 and 31 are carried by spring 95 holders 32 and 33. These holders comprise the overlapped portions 34 and the rearwardly directed finger pieces 35. One of the overlapping portions of each holder is provided with an inturned edge 36 adapted to engage 100 in any one of a plurality of notches 37 formed in the corresponding standards. When released these spring holders move to such position as to cause the inturned edge 36 to engage in the corresponding 105 notches 37 and thus hold the holder and the tooth carried thereby against vertical movement. By pressing the finger pieces toward each other the inturned edge 36 is forced out of the notch 37 and the holder may then 110 be adjusted vertically to cause the edge 36 to engage in another one of the notches 37.

The handle 21 is provided with an inwardly and downwardly projecting element 38 which carries a plurality of cleats 39 at its lower end. The cleats are mounted upon a rod 40 and said rod is being actuated inwardly by means of a spring 41 to thereby bind the cleats frictionally against each other. These cleats may be provided with engaging projections and recesses 43 and 44 respectively if desired. By thrusting the handle 21 downwardly and inwardly until the lowermost cleat clears the inner edge of the standards 16 and by then turning said cleat transversely the handle 21 will be held in its recessed position. If this degree of movement is not sufficient the handle may be depressed further to force another one of the cleats beyond the inner edge of the standard 16 to there be turned transversely in the manner aforesaid. From the foregoing description it will be seen that a spring setting device is here provided which is of simple and economical construction but wherein the parts are so arranged that a single movement of the handle 21 will be all that is necessary to set the leaves of a spring apart. The vertical adjustment provided by the arrangement of the teeth and holders upon the upper ends of the standards enables the user to quickly and easily treat the several leaves of the springs, while the capability of the standards to swing to varying angles with respect to the base 5, renders it possible to properly engage the teeth with those portions of the leaves of the springs which lie otherwise than horizontal.

It is to be understood that the invention is not limited to the precise construction set forth but that it includes within its purview whatever fairly comes within either the terms or the spirit of the appended claims.

Having described my invention, what I claim is:

1. A device of the character described comprising a ground engaging base, a pair of confronting standards pivotally connected at their lower ends to the base and supported in a substantially upright position thereby, manually operable means for moving the standards toward each other and wedge like spring engaging teeth mounted upon the upper ends of the standards adapt-

ed to enter between the leaves of a spring to force the same apart.

2. A structure as recited in claim 1 where- 55 in the spring engaging teeth are vertically adjustable with respect to the standards.

3. A structure as recited in claim 1 where- 60 in the standards are mounted to swing to varying angles laterally with respect to said base.

4. A device of the character described comprising a supporting base, a pair of standards pivotally connected to said base at their lower ends, an operating handle pivoted to one of 65 said standards, a link pivotally connected to said handle and slidably engaged with the other of said standards and spring engaging dogs mounted upon the upper ends of said standards. 70

5. A structure as recited in claim 4 where- 75 in said spring engaging dogs are vertically adjustable upon the upper ends of said standards.

6. In a device of the character described 75 a supporting base, an oscillatory block mounted in said base, a pair of standards pivotally connected at their lower ends to said oscillatory block, an operating handle pivoted to one of said standards, a link engaged with the other of said standards and with said handle, means for holding said handle in varying positions of adjustment and spring engaging dogs vertically adjustable upon the upper ends of said standards. 85

7. A structure as recited in claim 6 in combination with means for binding said oscillatory block in varying positions of adjust- 90 ments.

8. A device of the character described 90 comprising a pair of standards, means for moving said standards toward and from each other and a dog upon the upper end of each of said standards, each of said dogs comprising a tooth, a pair of overlapping 95 spring elements by which said tooth is carried, teeth upon the standards and a part adapted to engage the teeth of the standards to hold the dog in varying positions of vertical adjustment with respect to said standards. 100

In testimony whereof I affix my signature in the presence of two witnesses.

GOTTLIEB L. E. KLINGBEIL.
